Primary Examiner — Darlington Ly*Assistant Examiner* — D. Ryan Tisdale(74) *Attorney, Agent, or Firm* — Barnes & Thornburg LLP; Joan Taft Kluger**CLAIM**

I claim the ornamental design for a propeller, as shown and described.

DESCRIPTION

FIG. 1 is a perspective view of a propeller, showing my new design.

FIG. 2 is a front elevation view thereof.

FIG. 3 is a rear elevation view thereof.

FIG. 4 is a right side elevation view thereof.

FIG. 5 is a left side elevation view thereof.

FIG. 6 is a top plan view thereof; and,

FIG. 7 is a bottom plan view thereof.

The broken lines in FIGS. 1-7 represent portions of the propeller that form no part of the claimed design.

1 Claim, 7 Drawing Sheets(56)
